WILLIAM J. CROSSLEY AND THOMAS RIGBY, OF MANCHESTER, ENGLAND

GAS-PRODUCER.

SPECIFICATION forming part of Letters Patent No. 768,655, dated August 30, 1904

Application filed October 15, 1903. Serial No. 177,182. (No model.)

To all whom it may concern:

Be it known that we, WILLIAM JOHN CROSSLEY, engineer, of Openshaw, and THOMAS RIGBY, engineer, of 15 West Bank, Higher 5 Openshaw, Manchester, in the county of Lancaster, England, have invented certain new and useful Improvements in Gas-Producers, of which the following is a specification.

Our invention relates to improvements in those gas-producers in which the gas is drawn direct from the producer by suction or aspiration, such as is produced by the piston of a gas-engine. In such gas-producers great difficulty is experienced in making gas of uniformly-good quality in cases where a varying demand for gas is constantly changing the rate of combustion. When the steam necessary for the proper gasification of the fuel is raised by means of the heat of the 15 gases leaving the producer, the difficulties are increased, as the actual steam generation is difficult to keep proportionate to the quantity of gas being made. If the plant is working at full load and the rate of combustion is at 20 the maximum, it is easy to maintain a uniformly-good quality of gas; but if the demand suddenly decreases to any extent—say to fifty per cent. of the maximum—the quantity of steam raised is not readily reduced to the 25 proper proportion. As a consequence an excess of steam is passed through the producer until such time as the steam making readjusts itself and again becomes properly proportioned to the requirements. While steam is 30 being generated in excess the heat of the fire is thereby reduced, thus making it impossible to keep the gas of uniform quality.

The chief object of our invention is to effect the better regulation of the steam proportion 35 in the mixture of air and steam supplied to the producer. We have discovered that the working of the producer is improved and a more uniformly good quality of gas is obtained by keeping the proportion of steam to 40 air at a minimum at the light loads and raising it in an increasing ratio to a maximum proportion at full load. We attain this result by causing a portion of the air-supply (which we will call the "primary" air-supply) 45 to be taken direct to the fire and by passing

the remainder (which we will call the "secondary" air-supply) through the steam-raising chamber in the first place, so as to saturate it with steam, then conducting it to the primary air-supply in the second place, and 55 causing the combined primary and secondary air-supplies to enter the fire mixed together.

Our invention has for its second object to prevent the formation of holes and cavities in the fuel-bed. A common defect of producer 60 fire-grates is that any clinker formed is liable to cling to the internal brickwork sides of the producer, and so cause adhesion and hanging of the fuel, with consequent formation of holes and cavities in the fuel-bed. According to 65 our invention we overcome this defect and accomplish our second object by arranging the fire some few inches below the brickwork and causing all the air and steam to pass into the fire from the under side of the fire-grate only. 70

To enable our invention to be fully understood and readily carried into effect, we will further describe the same with reference to the accompanying sheet of drawings, in which—

Figure 1 is a sectional elevation of a suction gas-producer made according to our improvements. Fig. 2 is a half-section plan of the same, the right-hand half showing a plan on the line Z Z, indicated by Fig. 1, and the left-hand half a plan of the top of the producer. 75 Fig. 3 is a sectional plan on the line Y Y, Fig. 1.

In the construction illustrated we arrange the fire-grate *a* some few inches below the brickwork *b*, as shown in Fig. 1, and as the most intense heat of the fuel is near the fire-grate *a* any clinker formed is generally formed there and in this case away from the nearest brickwork *b*. By this construction and arrangement there is nothing to prevent the easy descent of the fuel, because no clinker 80 forms and clings to the internal brickwork sides of the producer, and consequently the tendency to form holes and cavities in the fuel-bed is entirely obviated in our construction.

To prevent loss by radiation of the intense 95 heat of the fire, box-castings *c* or other similar devices are used as superheaters and are preferably fixed concentrically with the fire, thereby forming a pair of semicircular box-castings, as clearly shown in Fig. 3. They 100

are carried by the plate d , which also carries the fire-grate a , this in turn being supported by the external casing of the producer e . The top sides of the castings or superheaters c provide a convenient support for the circular plate f , which carries the brickwork lining of the producer.

The external casing of the producer is preferably made in the form of a cylindrical casting e , with doors g and h above and below the fire-grate to facilitate removal of the ashes, the bottom being inclosed. The top is covered by the horizontal plate-casting or steam-raising device k , which also acts as a storage for coal, as shown in Fig. 1. The under side of the plate is preferably arranged with a number of concentric rings m , the lower portion of the rings being secured in the brickwork. The hot gas leaving the producer is passed through the spaces formed by the rings in succession, starting near the center and traveling in a circular direction, passing from ring to ring through the spaces shown at n till the gas-outlet pipe p is reached. By this means intimate contact of the gas is obtained with the whole of the plate, the upper portion being covered with a layer of water. The rings may be arranged, if desired, in a continuous spiral or helix in preference to the concentric arrangement. The inner diameter of the boiler being used as a reservoir of fuel is fed by a suitable charging-hopper s , also arranged as a further reservoir of fuel. Water, in the first place, is fed into the annular space of the steam-raising apparatus k by means of a feed-pipe t , whence it flows over the plate k , the overflow-pipe a^2 being provided to insure a constant water-level. A suitable steam-space is arranged above the water-level and is inclosed by the plate d^3 , covered with non-conducting materials a^4 . Vertical pipes c^2 are arranged with their ends inside the steam-space well above the water-level, the lower portions passing down through the water and steam raising device and the plate f and between the brick-work and the external casing and the lower ends of the pipes c^2 being secured into the superheaters c . This is done in such a manner that anything passing through them is made to traverse the whole length of the superheaters c before being conducted to the under side of the fire-grate by means of the connections c^3 , thus making the heating surfaces effective.

All the air or air and steam entering the fire is passed through the fire-grate from the under side thereof, and this is one of the features of the invention, as it insures all intense combustion taking place near the fire-grate and away from the brickwork.

The producer is started to work by blowing air into the fire by means of a hand-fan g^2 , which causes the fire to become hot enough to make gas suitable for starting the gas-engine.

The primary portion of the air-supply ac-

cording to our invention is drawn direct to the fire through the hand-fan g^2 , and the remainder or secondary air-supply is drawn through the cock g^3 and the steam-raising chamber, in the first place, so as to saturate it with steam, and then by way of the pipes c^2 and the superheaters c through the short pipes c^3 to the under side of the fire-grate, in the second place, the primary air and the secondary air thus entering the fire mixed together. The primary air-supply is arranged in close proximity to the fire, the secondary air being preferably a greater distance away.

The area of the primary air-inlet is usually constricted somewhat with the object of causing the suction to be felt more or less in the steam-chamber and at the secondary air-supply cock. This is done by means of the damper m^2 directly under the hand-fan g^2 . By this arrangement when the load is at a maximum a larger proportion of secondary air to be saturated with steam will be drawn through the cock g^3 than when working at the lighter loads. It should be understood that the primary air receiving the first effects of the suction of the engine-piston will always be working at the fullest rate the constricted orifice will allow even on the lowest load. As the demand for gas increases, the quantity of secondary air and steam drawn in will necessarily increase, reaching the maximum at full load, thus insuring in the mixture a larger proportion of steam to air at full load than at light load. Any surplus steam due to sudden changes of the load will escape through the secondary air-inlet cock g^3 .

We do not limit our claims for this regulating device to a suction-producer in which steam is raised from the heat of the gases leaving the producer, as we may use a similar arrangement in cases where the steam necessary for efficient gasification of the fuel is raised independently by any other means. In such a case we should draw the secondary air-supply through any suitable steam-mixing chamber in the first place and then allow the primary air and secondary air loaded with steam to enter the fire mixed together, as before described.

The gas after leaving the producer may be washed and scrubbed or treated as may be desired.

The various constructional details of the producer described herein may be of any suitable material for such a purpose.

What we claim as our invention, and desire to secure by Letters Patent of the United States, is—

1. In combination in a suction gas-producer, a steam-chamber, a fire-grate, a primary air-supply for the producer a secondary air-supply passing through the steam-chamber so as to vary the proportion of steam to air corresponding to the load and means for delivering the primary air and secondary air and

steam to the under side of the fire-grate so that they will mix and enter the fire together, substantially as described.

2. In combination in a suction gas-producer, 5 a steam-chamber, a fire-grate, a box-casting surrounding the grate, a primary air-supply, a secondary air-supply, said secondary air-supply being connected with the steam-chamber, and the box-casting whereby the air is 10 superheated and means for delivering the primary air and the secondary air and steam to the under side of the grate so that they will mix and pass into the fire together, substantially as described.
- 15 3. In suction gas-producer plants, a steam-chamber, a constant primary air-supply, in combination with a variable secondary air-supply for the plant, said secondary air-supply entering the steam-chamber on its passage

to the combustion-point whereby the proportion of steam to air will vary according to the load.

4. In combination in a suction gas-producer, a casing a lining therefor, a grate below said lining, a pair of semicircular box-castings between said grate and lining, said castings having steam and air inlet ports at one end and outlet-ports at the opposite end so that the steam and air will pass through said castings to the under side of the grate and rise 20 through the same.

In witness whereof we have hereunto set our hands in presence of two witnesses.

W. J. CROSSLEY.
T. RIGBY.
